FUSE BLOCK AND PARTS THEREOF

Harrison J. L. Frank, Detroit, Mich.

Application February 3, 1938, Serial No. 188,501

12 Claims. (Cl. 200—133)

The inventions of this application relate to fuse blocks and parts thereof and particularly to fuse blocks formed for receiving plug fuses.

Generally speaking, the inventions hereof relate to the type of fuse block that comprises a block of insulating material mounting a bus bar to which a line conductor is connected: in the block is provided a socket or depression containing a screw shell for the reception of a plug fuse: a branch conductor is mechanically and electrically connected to the screw shell and the circuit is established between the line conductor and the branch conductor through the bus bar, the plug fuse, and the screw shell.

One invention aims to provide a construction wherein electrical connection between the plug fuse and the bus bar is established by direct engagement between the bus bar and the tip contact of the plug fuse.

Another invention aims to provide a novel mechanical and electrical connection between the terminal of the branch conductor and the screw shell, with such connection being established by the action of threading the plug fuse into the screw shell.

Still other inventions aim to provide novel details of construction of fuse blocks.

The inventions hereof will best be understood by reference to the following description of the embodiments thereof that are shown in the appended drawings. In these drawings,

Fig. 1 is a top plan view of a fuse block of the invention, with one of the two sockets shown as equipped with a plug fuse and with parts cut away for purposes of clarity;

Fig. 2 is a section on line 2—2 of Fig. 1;

Figs. 3, 3a and 3b are sections on line 3—3 of Fig. 1, but showing the parts in their various positions;

Figs. 4 and 4a are views of modified forms of screw shells;

Fig. 5 is a plan view of a modification;

Figs. 6 and 6a are cutaway views of this modification with the parts shown in their various positions.

Fig. 7 is a plan view of still another modification;

Figs. 8 and 8a are cut away views of this modification with the parts shown in their various positions;

Fig. 9 shows a resiliently formed bus bar and a modified form of screw shell.

Figs. 10—12 are views of a modification with the parts in their various relative positions.

Figs. 13—14 are sections on lines 13—13, 14—14, of Figs. 10 and 12 respectively.

Referring to the drawings, and more particularly to Figs. 1—3, it will be observed that these figures show a fuse block 10 of insulation material in whose top surface are formed round sockets 11, each containing a screw shell 12. Through four aligned holes 14 of two of such screw shells is passed an abutment in the nature of a bus bar 15 to an end of which is connected, by a suitable connection means 16, a line conductor 17.

Formed in the two screw shells at angles of 90° with respect to the line of the holes 14 are two additional holes 20 aligned with two holes 21 formed in the side edge of the block for the reception of the terminals 22 of branch circuit conductors 23, which when entered into the screw shells through the holes 21 and 20 will dispose themselves under the bus bar 15 and at right angles thereto.

Suitable insulation means insulates the branch circuit conductor terminals 22 from the bus bar 15. In the embodiments shown such insulation means comprises a U-shaped sleeve 24 disposed around the bus bar and engaging the bottom and side edges of the bus bar. Other insulating means, such as sleeves on the terminals 22, where they are directly in line with the bus bar, might also be used.

When the parts are associated as shown in the drawings, Fig. 1, lower part of Fig. 2, and Fig. 3, with the terminals 22 under, transverse of, spaced from, and in line with the bus bar 15, and with these passing through the holes 14 of the shells 12, and with the ends of the bus bar resting on the two block ledges 25 and secured with respect to the block by the screw 26, the act of threading a plug fuse 27 into a screw shell will serve to effect proper mechanical and electrical connection of the parts. The plug fuse tip 28 will first engage the top or bar surface of the bus bar to effect electrical connection between the plug fuse and the bus bar, and, consequently, between the bus bar and the screw shell, through the fuse, and will then pull the screw shell upwardly from the position of Fig. 3 to that of Fig. 3a and then to that of Fig. 3b, wherein the lower edge of the hole 20 of the screw shell will bite into the terminal 22, and with this terminal kinked as shown at Fig. 3b to be properly interlocked to the screw shell and properly pressed against the bottom of the screw shell to effect mechanical and electrical connection between the branch conductor and the screw shell, with the net result that all the

parts are firmly secured in the block and proper electrical connection from the line conductor 17 to the branch conductor 23 through the plug fuse is established.

5 Whereas in the modification of Figs. 1-3 each screw shell is shown as having but one hole 20 for the reception of a terminal 22, as an alternative the expedient shown in Fig. 4 may be utilized. This figure shows each screw shell as having two aligned holes 20 through which the terminal 22 is passed and, as shown in Fig. 4, the threading in of the plug fuse into the shell will provide a double kink in each terminal and a multiple point engagement of the terminal with the screw shell holes 20.

It will also be observed that the engagement of the terminal with the bottom edge of the screw shell hole or holes 20 is in the nature of a biting engagement, such bottom edge of the hole 20 cutting through any film that may improperly exist on the terminal 22.

If desired, the hole 20 may be formed as shown in Fig. 4a, tapered to provide a large part receiving terminal 22 and a small part into which such terminal may be wedged, as shown.

Figs. 5 and 6 show a modification wherein the screw shell is in the form of a strap 30. Such strap comprises a bottom part 31 and two side parts 32 whose free edges are provided with interior parts 33 terminating in tips 34 having tongues 35 on their ends fitting in holes 36 of the strap side parts 32. Threads are formed in the facing surfaces of the interior parts 33 for threaded cooperation with the plug fuse 27. Kinks are formed in the bottom part 31 and in the tips 34 for biting engagement with a terminal 22 thrust into the strap through the aligned holes 36 formed in the sides 32 of the strap.

40 It will be observed that when a terminal 22 is thrust into a strap through a block hole 21 and the strap holes 36 and thereafter a plug fuse 27 is threaded into the strap, cooperating with the threads, that the tip 28 of the fuse will engage the bus bar 15 and pull up on the strap and at the same time move the interior parts 33 and their tips 34 into the position of Fig. 6a from that of Fig. 6 to cause the kinks in the tips and in the bottom of the strap to bite into the terminal and effect good binding contact between the terminal and the strap. At the same time, tongues 35 will wedge into holes 36 and bind terminals 22 in these holes.

It will also be observed that the socket 11 in which is disposed the strap 30 has side slots 38 receiving the side parts 32 of the strap. The disposition of the side parts of the strap in the side slots of the socket eliminates the possibility of objectionable relative sidewise shifting of the strap and the block.

It will be observed that the tunnel between tip 34 and the shell bottom 31 is in effect a continuation of the side hole 36 and that tip 34 is in effect a side edge or wall of such tunnel.

65 It will also be observed that in any embodiment here shown there are clear side spaces in the shell through which the bus bar and conductor pass. Holes 14 and the spaces between parts 33 are such spaces; and holes 20 and 36, as well as the tunnels between parts 31 and 34, are also such spaces.

70 It will also be observed that while the abutment, with respect to which the screw shell 12 is moved relatively, is shown as a bus bar 15, it need not be such, but may be any suitable means;

for example, it may be a terminal of a conventional insulated wire.

Further, that in the arrangement shown, the abutment (bus bar) 15 and the terminal 22, function to prevent rotation of the shell 12 in the socket 11.

In the modification shown in Figs. 7-8, which modification closely resembles that of Figs. 5-6, the tongues 34 are shown as formed with extensions 41 adapted to engage strap parts 33 to limit 10 inward motion of the threaded parts 33 when these parts are spread apart by the spreading cone of a plug fuse 27, the part 41 acting as positive stops. Further, there are shown tongues 42 bent downwardly from the strap and provided 15 with holes through which pass the terminal 22. These tongues provide a positive interlock between the strap parts 33 and the terminal 22 to prevent axial separation of these parts relatively.

It will also be noted that the block 10 is so formed as to provide a recess having an upper surface 43 for seating the free ends of the terminal 22.

It will also be observed that in this modification the block side slots 38 are formed with ribs 44 which closely hug the lower ends of the strap parts 33 and thus aid in preventing these strap parts from twisting out of shape and helps lock these parts in position.

It will also be observed that in this modification of Fig. 9, which closely resembles that of Figs. 1 to 4, the bus bar 15 is shown as provided with a cutout 45 in which is disposed a copper leaf spring 50 of corrugated form and having its ends secured to the bus bar 35 to provide a resilient seat for the plug fuse and thus to resiliently clamp the latter against rotation for loosening in the shell 12 and at the same time to provide a resilient clamp on the wire terminal 20.

40 In addition, the screw shell is shown as provided with tongues 51 which seat within sockets 52 formed in the main socket 11 of the block, the tongues cooperating with the side walls of the supplementary sockets 52 to aid in limiting 45 twisting of the screw shell in the socket 11.

In assembling the parts, the shells are placed in their sockets, the bus bars are passed through the blocks and the shells to hold the shells in place, the screws 26 are then threaded home to 50 fasten the bus bars in place, then the terminals 22 are passed through the blocks and into the shells, and finally the fuses are threaded home to fasten the terminals in place and to bind them into electrical engagement with all the parts.

55 In the modification of Figs. 10-14, the bottom of the screw shell 12 is perforated, as at 60, to receive the bent part 61 of a springy washer or strap 62 formed as shown, to interlock the terminal 22 and the screw shell, when the terminal is threaded through the shell holes 20 and the washer bend 61, and lies in the transverse grooves 63 of the shell bottom. Threading a plug fuse 27 down into the shell pulls up on the shell, washer, and terminal, until the tip 28 engages 65 the bus bar 15, and the washer engages the insulation 24 around the bus bar.

Now having described the fuse block hereof in its various embodiments and the inventions hereof as embodied in the device shown in the appended drawings, reference will be had to the claims which follow for a determination of the inventions.

I claim:

1. A block having a socket, a screw shell there-

in, a bus bar passing through a hole in a side of the shell and insulated from the shell, a conductor passing through another hole in the shell and passing transversely under and insulated from the bus bar, whereby a tip and sleeve contact device threaded into the shell will have its tip engage the bus bar and cause relative movement of the bus bar, the shell, and the conductor with the conductor engaging and making electrical contact with the shell and kept out of electrical contact with the bus bar.

2. A block having a screw shell, a bus bar passing through a clear side space of the shell, a conductor also passing through a clear side space 15 of the shell, with the bus bar between the conductor and the open end of the shell, and with the bus bar insulated from the shell and the conductor, whereby a tip and sleeve contact type device, when threaded into the shell, will have its tip contact engage the bus bar to cause relative movement of the bus bar, the shell, and the conductor, with the shell and the conductor making mechanical and electrical contact with each other, and with the bus bar making insulated mechanical contact with the shell and conductor, and with the sleeve contact of the device making mechanical and electrical contact with the shell.

3. In combination, a screw shell having a side 30 hole, a conductor terminal therein, an abutment in the shell, and a tip and sleeve contact device for threading into the shell and engaging the abutment and moving the shell and conductor relatively to bind the conductor against an edge 35 of the side hole.

4. In combination, a screw shell having a side hole, a conductor terminal therein, an abutment in the shell, and a tip and sleeve contact device for threading into the shell and engaging the abutment and moving the shell and conductor relatively to bind the conductor against an edge 40 of the side hole, with the conductor also bound between the shell and the abutment.

5. In combination, a screw shell having a side 45 hole, a conductor terminal therein, an abutment in the shell, and a tip and sleeve contact device for threading into the shell and engaging the abutment and moving the shell and conductor relatively to bind the conductor against an edge 50 of the side hole, with electrical contact between the conductor and shell, between the shell and the side of the device, and between the tip of the device and the abutment, and means for insulating the abutment from the shell and conductor.

6. In combination, a screw shell having a side 55 hole, a conductor terminal therein, an abutment in the shell, and a tip and sleeve contact device for threading into the shell and engaging the abutment and moving the shell and conductor relatively to bind the conductor against an edge 60 of the side hole, with the conductor also bound between the shell and the abutment, with electrical contact between the conductor and shell, between the shell and the side of the device, and between the tip of the device and the abutment, and means for insulating the abutment from the shell and conductor.

7. In combination, a screw shell having a side 65 hole, a conductor terminal therein, an abutment

in the shell, and a tip and sleeve contact device for threading into the shell and engaging the abutment and moving the shell and conductor relatively to bind the conductor against a flanged edge of the side hole.

8. In combination, a screw shell having a side hole, a conductor terminal therein, an abutment in the shell, and a tip and sleeve contact device for threading into the shell and engaging the abutment and moving the shell and conductor relatively to bind the conductor against a flanged edge of the side hole, with the conductor also bound between the shell and the abutment.

9. In combination, a screw shell having a side hole, a conductor terminal therein, an abutment in the shell, and a tip and sleeve contact device for threading into the shell and engaging the abutment and moving the shell and conductor relatively to bind the conductor against a flanged edge of the side hole, with electrical contact between the conductor and shell, between the shell and the side of the device, and between the tip of the device and the abutment, and means for insulating the abutment from the shell and conductor.

10. In combination, a screw shell having a side hole, a conductor terminal therein, an abutment in the shell, and a tip and sleeve contact device for threading into the shell and engaging the abutment and moving the shell and conductor relatively to bind the conductor against a flanged edge of the side hole, with the conductor also bound between the shell and the abutment, with electrical contact between the conductor and shell, between the shell and the side of the device, and between the tip of the device and the abutment, and means for insulating the abutment from the shell and conductor.

11. A screw shell, a conductor passing through a hole in a side of the shell and insulated from the shell, a conductor passing through another hole in the shell and passing transversely under and insulated from the first mentioned conductor, whereby a tip and sleeve contact device threaded into the shell will have its tip engage the first mentioned conductor and cause relative movement of the shell, and the two conductors, with the second mentioned conductor engaging and making electrical contact with the shell and kept out of electrical contact with the first mentioned conductor.

12. A screw shell, a conductor passing through a clear side space of the shell, a second conductor also passing through a clear side space of the shell, with the first conductor between the second conductor and the open end of the shell, and with the first conductor insulated from the shell and the second conductor, whereby a tip and sleeve contact type device, when threaded into the shell, will have its tip contact engage the first conductor to cause relative movement of the shell, and the two conductors, with the shell and the second conductor making mechanical and electrical contact with each other, and with the first conductor making insulated mechanical contact with the shell and second conductor, and with the sleeve contact of the device making mechanical and electrical contact with the shell.

HARRISON J. L. FRANK.
